UNITED STATES PATENT OFFICE.

WALTER R. ARMSTRONG, OF CHICAGO, ILLINOIS, ASSIGNOR OF ONE-HALF TO
FRANKLIN MAYO, OF CHICAGO, ILLINOIS.

MERCURY SWITCH.

Application filed April 6, 1928. Serial No. 267,857.

My invention relates to mercury switches of the kind wherein a quantity of mercury within a tilting tube acts to establish and break a circuit having its conductors terminating in the tube.

Tilting mercury switches which have been known and used for many years have been of two general types, namely those wherein opening and closing of a circuit is effected by 10 the separation and coming together of portions of a body of mercury, and those wherein the mercury does not separate but, in its movements, engages and disengages with one of a pair of fixed electrodes to establish 15 and break a conducting path between a pair of such electrodes.

All of these mercury switches with which we have heretofore been familiar have been subject to certain serious objections when 20 utilized to interrupt the flow of currents of any considerable ampere strength,—objections which have come to be regarded as inherent and unavoidable in this kind of switch.

The impingement of recurring arcs upon 25 the glass or other material of the tube detaches small particles of the tube material at or adjacent the point wherein the arcing occurs and eventually causes disruption of the tube. Moreover, the co-mingling of the detached 30 particles of the tube material with the mercury tends to make the action of the latter more sluggish than is desirable. Pitting of the tube by arcing also oftentimes impairs the performance of the mercury. Furthermore, 35 the continuous occurrence of substantial arcs in the mercury switch has an objectionable effect upon the mercury, making its flow sluggish and causing the mercury and/or impurities therein contained to give off gases which 40 cloud the tube, which preferably should be transparent.

The disadvantages just mentioned are practically eliminated by the present invention, two characteristic embodiments of which are 45 illustrated in the accompanying drawing.

In the drawing:

Figure 1 is a longitudinal section of a 50 switch tube and its associated parts constructed and arranged in accordance with my present invention,—the conventional tube holding and tilting mechanism being omitted, and the circuit connections being diagrammatically illustrated; and

Figure 2 is a similar view illustrating a 55 modified embodiment of the invention, where-

in the reduction and interruption of the current flow is effected by the actual disengagement of the mercury from fixed electrodes, as distinguished from the arrangement of Figure 1, wherein the reduction and interruption of the current flow is accomplished by separation of the mercury into disconnected portions.

Referring to the drawings, the switch tube, 60 preferably formed of glass, is illustrated at 3, this tube containing a quantity of mercury 4 and also preferably containing one of the gases found suitable for use in these tilting mercury switches, for instance, hydrogen.

Ordinarily, as is well understood in the art, 65 these tubes are supported upon a tilting mechanism (not shown), which in turn is acted upon by a suitable controlling or operating mechanism to tilt the tube when the circuit controlled by the switch is to be completed or broken. For the purposes of the 70 present description, it may be assumed that the tube moves in a vertical plane around the axis or fulcrum F, being tilted in the direction of the feathered arrow A when the circuit is to be opened, and being tilted in the direction of the unfeathered arrow B when the circuit is to be closed.

The tube shown in Figure 1 is provided 75 with three depressions or wells 5, 6 and 7, a certain portion of the mercury always remaining in each of these wells. Ordinarily, 80 the tube 3 will be tilted in the direction of the feathered arrow A sufficiently to cause the main body of mercury 4 successively to separate itself from the mercury contained in the wells 5 and 6, but not necessarily sufficiently 85 to cause a separation of the main body of mercury from the portion contained in the well 7. Thus, for the purpose of the specification and the appended claims, mercury 90 portions which always remain in the wells 5 and 6 may be regarded as mercury electrodes from which the main body of mercury 4 is 95 detached and with which the said main body of mercury is caused to join for the purposes hereinafter explained.

The wells 5, 6 and 7 are conveniently located in bosses or enlarged portions of the 100 tube wall, as illustrated. Entering each of these enlarged portions is a lead in wire 8, conveniently of copper, the inner end of which is connected in the usual manner with a suitable metal alloy 9, which is imbedded 105 in the glass and has substantially the same 110

coefficient of expansion as the glass. From each of the elements 9 extends a short conductor 10, which is at all times in electrical contact with the mercury portion contained 5 in the well into which it projects. The conductors 10 are preferably formed of iron or other material which will not become amalgamated with mercury. Whenever the conductors 10 are not formed of iron, the portions 10 thereof, which otherwise would be exposed to contact with the mercury, may be protected by small sleeves 11 of iron, carbon or the like. The sleeves 11 also serve the purpose of increasing the surface contact 15 between the mercury and the conductors projecting into the wells.

At C and C' are indicated the conductors of a circuit controlled by my improved switch, the conductor C being at all times 20 connected with the mercury electrode 8, and the conductor C' being at all times connected with the mercury electrode 5. Mercury electrode 6 is at all times connected through a relatively high resistance 12 with the mercury electrode 5.

It will be understood without illustration that the conductors connecting with the lead in wires 8 will be sufficiently flexible to permit ready tilting of the tube, and that the 30 resistance winding 12 will preferably, but not necessarily, be mounted at some convenient point upon the tube holding and tilting mechanism.

With the tube in the position shown in 35 Figure 1, the circuit controlled by the switch will be closed without encountering any appreciable resistance in the switch. Upon tilting of the tube in the direction of the arrow A, the main body of mercury will move toward 40 the lower end of the tube, the first result of this movement being a physical separation of the main body of mercury from that which always occupies the well 5. This separation of the mercury electrode in the 45 well 5 from the main body of mercury is not accompanied by any arc, or any substantial arc, due to the continuance of current flow through the high resistance path, including the resistance 12. Ordinarily the coil or 50 winding 12 will have such resistance as to reduce the current flow by eighty or ninety percent immediately following the interruption of the low resistance path through the switch. Almost immediately following the 55 interruption of the low resistance path, the high resistance path, including the winding 12, will be interrupted by the separation of the main body of mercury from the mercury

always occupying the well 6, but in this instance there will be no arc, or any appreciable arc, due to the fact that the current now flowing is an extremely small part of the normal current flow. The circuit controlled by the switch is now opened. On reverse tilting of the tube, in the direction 65 of the arrow B, the circuit controlled by the switch is first closed through the resistance winding 12, and is then almost immediately given a low resistance path around the resistance 12, when the main body of mercury 70 joins the mercury contained in the well 5.

The embodiment of my invention illustrated in Figure 2 requires no particular comment, except perhaps to say that in this instance the electrodes 5, 6 and 7 are fixed 75 electrodes, preferably of iron, with which the mercury 4 makes and breaks contact when the tube is tilted to and fro.

Either of the constructions illustrated in the accompanying drawings will eliminate 80 and/or minimize all of the hereinbefore mentioned objections of the two electrode mercury switches of the prior art. I believe I am the first to suggest providing a tilting mercury switch with a multiplicity of electrodes and/or a resistance for the purposes 85 herein set forth.

Having thus described two practical embodiments of my invention, I do not limit myself to the particular constructions herein set forth, but wish to cover all the equivalent constructions falling within the terms and spirit of the appended claims.

What I claim as new and desire to secure by Letters Patent of the United States, is: 95

1. A mercury switch comprising a tube tiltable about a fulcrum, a quantity of mercury in said tube, three spaced electrodes extending into said tube through one end thereof and terminating at different distances 100 from the fulcrum of said tube, the said electrodes also being spaced from each other so that contact with the mercury is made and broken serially.

2. A mercury switch comprising a tube 105 tiltable about a fulcrum, three spaced electrodes extending into said tube through one end thereof and terminating in downturned ends spaced from each other and at different distances from the fulcrum of the tube 110 whereby contact will be made and broken serially.

In witness whereof, I hereunto subscribe my name this 3rd day of April, 1928.

WALTER R. ARMSTRONG.
